DESIGN FOR A BLOW VALVE OR SIMILAR ARTICLE

James E. Becker, Lakewood, Ohio, assignor to
The Cleveland Vibrator Company, Cleveland,
Ohio, a corporation of Ohio

Application June 16, 1945, Serial No. 120,160

Term of patent 14 years

(Cl. D78—1)

To all whom it may concern:

Be it known that I, James E. Becker, a citizen of the United States and a resident of Lakewood, in the county of Cuyahoga and State of Ohio, have invented a new, original, and ornamental Design for a Blow Valve or Similar Article, of which the following is a specification, reference being had to the accompanying drawing, forming a part thereof.

In the drawing:

Fig. 1 is a perspective view of a blow valve or similar article, showing my new design with the manual control lever in closed position;

Fig. 2 is a side elevational view thereof;
Fig. 3 is a similar view with the lever in open position;

Fig. 4 is a front elevational, and
Fig. 5 is a rear elevational view thereof.

I claim:

The ornamental design for a blow valve or similar article, substantially as shown and described.

JAMES E. BECKER.
